(57) **CLAIM**

We claim the ornamental design for a hard case for carrying sporting equipment, as shown and described.

DESCRIPTION

FIG. 1 is a perspective view of a hard case for carrying sporting equipment according to the invention.

FIG. 2 is a top elevational view of a hard case for carrying sporting equipment according to the invention.

FIG. 3 is a left side view of a hard case for carrying sporting equipment according to the invention, the right side being a mirror image thereof.

FIG. 4 is a rear view of a hard case for carrying sporting equipment according to the invention.

FIG. 5 is a front view of a hard case for carrying sporting equipment according to the invention; and,

FIG. 6 is a bottom elevational view of a hard case for carrying sporting equipment according to the invention.

The broken lines showing a tubular element are for the purposes of illustrating environment and form no part of the claimed design.
